(57) **CLAIM**

The ornamental design for an implanting, sensing and reading device, as shown and described.

DESCRIPTION

FIG. 1 is a perspective view taken from a front, right side of an implanting, sensing and reading device according to an embodiment of our design;

FIG. 2 is a perspective view taken from a front, right side of an inserting unit of the implanting, sensing and reading device of FIG. 1;

FIG. 3 is a top plan view thereof;

FIG. 4 is a close-up view of portion 4 of FIG. 3;

FIG. 5 is a bottom plan view of the inserting unit of the implanting, sensing and reading device of FIG. 2;

FIG. 6 is a close-up view of portion 6 of FIG. 5;

FIG. 7 is a perspective view taken from a front, right side of a sensing and reading unit of the implanting, sensing and reading device of FIG. 1;

FIG. 8 is a top plan view thereof; and,

FIG. 9 is a bottom plan view thereof.

The even length broken lines in FIGS. 3, 4, 5, and 6 are for the purpose of depicting the boundary lines of the partial, enlarged figure views and form no part of the claimed design. The dot-dash lines illustrate boundaries of the claimed design and also do not form part of the claimed design. The dotted lines throughout the figure views show portions of the implanting, sensing, and reading device that form no part of the claimed design.

The implanting, sensing, and reading device is shown with breakaway lines in FIGS. 1, 2, 3, 5, 7, 8, and 9. The appearance of any portion of the device between the breakaway lines forms no part of the claimed design.
